UNITED STATES PATENT OFFICE.

GEORGE E. CLEVELAND, OF FREEDOM, PENNSYLVANIA, ASSIGNOR, BY MESNE ASSIGNMENTS, OF ONE-HALF TO MATILDA OVER, OF MUNCIE, INDIANA.

GLASS-PRESSING APPARATUS.

SPECIFICATION forming part of Letters Patent No. 628,157, dated July 4, 1899.

Application filed October 14, 1898. Serial No. 693,474. (No model.)

To all whom it may concern:

Be it known that I, GEORGE E. CLEVELAND, a citizen of the United States, residing at Freedom, in the county of Beaver and State of 5 Pennsylvania, have invented or discovered certain new and useful Improvements in Glass-Pressing Apparatus, of which improvements the following is a specification.

The invention described herein relates to 10 certain improvements in glass-presses, said improvements being applicable to the ordinary single-plunger presses and also to multiple-plunger presses in which a series of plungers are so mounted as to be capable of being 15 shifted in succession to position for actuation by the operating mechanism.

The invention has for its object a construction of plunger-actuating mechanism whereby the plunger may be positively actuated for 20 effecting the initial shaping operation, but will be actuated and held during the final shaping and setting of the glass through the medium of a spring or other yielding mechanism.

25 The invention is hereinafter more fully described and claimed.

In the accompanying drawings, forming a part of this specification, Figure 1 is a side elevation of my improved plunger-operating mechanism. Fig. 2 is a view, partly in front elevation and partly in section, showing the plunger and its actuating mechanism when the former is raised. Fig. 3 is a similar view showing the position of the parts at the end 35 of the positive movement of the plunger. Fig. 3^a is a detail view of a portion of the actuating mechanism in the position shown in Fig. 3. Figs. 4 and 5 are views similar to Figs. 1 and 2, illustrating a modification in the plunger-actuating mechanism. In Fig. 5 is shown 40 also means for preventing breakage of the apparatus when too great a quantity of molten metal has been placed in the mold.

For convenience of illustration and description my improvements are shown and described as applied to a single press; but its adaptation to other forms of presses will be obvious to those skilled in the art.

As shown in Figs. 1, 2, and 3, the power- 45 shaft 1 is mounted in suitable bearings se-

cured to the frame of the press. Arms or disks 2, preferably provided with radial slots, are secured on the projecting ends of the shaft, and pins 3 are adjustably secured in said slots. These pins are connected by rods 4 to the ends 55 of the cross-head 5, which is guided in its vertical movements by the posts or standards 6, secured to the bed of the press. Arms 7 have their inner ends secured on the pins 3 outside of the rods 4, and pins 8 are attached 60 to the outer ends of these arms preferably in such manner as to permit of the adjustment of the pins 8 along the slots 9 in the arc of a circle toward and from the pins 3, as clearly shown in Figs. 1 and 3^a. The pins 8 are connected by rods 10 to the ends of the cross-head 11, movably mounted on the posts or standards 6 above the cross-head 5. The cross-heads 5 and 11 are provided at points approximately midway between the posts or standards with vertical openings, through which the plunger-actuating rod 12 passes loosely. In order that the plunger-actuating rod may be forced down by the cross-heads, collars 13 and 14 are secured to the rod below the cross-heads. The collar 13 is so located on the rod 12 that the cross-head 5 will bear directly thereon during its downward movement, so as to positively shift the plunger; but a spring 15 is interposed between the collar 14 and the 70 cross-head 11, so that the plunger-rod will be yieldingly actuated by said cross-head. The rod 12 is raised by the cross-head 11 through the medium of a spring 16, interposed between 75 said cross-head and a collar 17 on the rod, or 80 by other suitable means.

While it is preferred to so adjust the arms 7 on the pins 3 that the pins 8 will move along arcs of circles of greater radius than the circle described by the pins 3, the pins 3 and 8 may be adjusted an equal distance from the axis of the shaft; but in the latter case the collar 14 should be adjusted on the rod 12, so as to hold the spring 15 constantly under a tension equal to the pressure to be exerted 90 on the glass.

In operating my press the glass is placed in the mold 18 and the latter shifted to position under the plunger 19. On the rotation of the shaft 1 in the direction of the arrow *a* the 100

cross-heads are drawn down. It will be observed, however, that as the arms 7 project backwardly as regards their direct rotation from the pins 3 the cross-head 5 will begin its downward movement in advance of the cross-head 11, although the pins 3 and 8 may move in circles of the same radius and having a common center. The actuating mechanism is so constructed that the plunger will 10 not be given its full movement by the cross-head 5, but will be given sufficient movement to approximately finish the article. This is clearly shown in Fig. 3, which shows the plunger in the lowest position to which it is 15 positively moved by the cross-head 5. By reference to Figs. 3 and 3^a, it will be seen that when the pins 3 and the cross-head 5 have reached the lower limit of their movements the pins 8 and cross-head 11 will be above the 20 lower limits of their movements. By the continued rotation of the shaft 1 the pins 8 and cross-head 11 will be moved down, so compressing the spring 15 that it will exert sufficient pressure of the plunger to force it down under a yielding pressure to complete the 25 shaping of the article. This spring-pressure will be exerted on the plunger for some time after the pins 8 have passed the power limits of their movements, so that the plunger will 30 be held down a sufficient time to permit the glass to set.

As it is practically impossible to charge the necessary amount of glass in a mold, it has heretofore been deemed impracticable to employ a positively-actuated plunger, as if a too large amount of glass were placed in the mold and the plunger moved its full stroke positively a portion of the glass would be squeezed out of the mold or the actuating 35 mechanism or mold would be broken.

It is characteristic of the operation of my invention that the most difficult part of the operation of molding glass—*i. e.*, starting the glass to flow or spread out along the walls of 45 the mold—is effected by positive pressure, while the comparatively easy portion of the operation—*i. e.*, continuing the flow of glass to final shape and holding it in such a position until the glass becomes set—is effected by 50 yielding pressure. This initial positive pressure and successive spring-pressure can be effected by many different forms of mechanism, and hence the invention as set forth in the terms of the claims are in no wise limited 55 to any specific construction of mechanism for operating the plunger.

In Figs. 4 and 5 I have shown another form of mechanism adapted to effect the operation of the plunger. This mechanism consists of 60 disks 20, loosely mounted on studs 21, secured to the posts 6 and provided on opposite sides with eccentric grooves for the reception of antifriction-rollers 22. These antifriction-rollers are secured to one end of the connecting-rods 4^a and 10^a, which have their opposite 65 ends connected to the ends of the cross-heads 5 and 11. The grooves in the faces of the

disks are so formed as to effect the movements of the cross-heads and plunger-actuating rod, as hereinbefore described. The disks 70 are rotated by pinions 23 on the driving-shaft 24, engaging teeth on the peripheries of the disks.

In Fig. 5 I have shown further a device for obviating possible damage to my machine 75 when carelessly operated. While it will be found that the method of operating the plunger by first a positive and then a yielding force, as above described, is amply sufficient to guard against breakage of the actuating mechanism or mold under ordinary usage, it will sometimes happen through the employment of unskilled or careless workmen that a quantity of molten metal considerably in excess of that required to produce 80 the finished article will be placed in the mold. In such a case the molten metal may fill the entire space between the mold and plunger before the plunger has reached the limit of its positive stroke, there being no further 85 space into which the molten metal can flow. Any further positive movement of the plunger into the mold will tend to break the mold or other parts of the machine. To guard against such accidents, I interpose, as illustrated in Fig. 5 of the drawings, a spring 25 between the cross-arm 5 and collar 13 of sufficient stiffness to withstand compression under ordinary operations; but under the conditions detailed above it will allow of sufficient compression to prevent further movement of the plunger into the mold while continuing to exert a yielding pressure upon the molten metal within the mold during the 90 balance of the operation, and thereby avoid 95 breakage of any part of the machine.

I claim herein as my invention—

1. In a glass-pressing apparatus, the combination of a plunger, plunger-actuating mechanism and connections between the actuating mechanism and the plunger, for driving the plunger positively during a portion of its stroke and applying a yielding force to the plunger to effect its final movement, substantially as set forth. 100

2. In a glass-pressing apparatus, the combination of a plunger, means for positively driving the plunger for a portion of its stroke and means for applying a yielding force to the plunger for effecting the final movement 110 thereof, substantially as set forth. 115

3. In a glass-pressing apparatus, the combination of a plunger, a plunger-actuating rod, two cross-heads adapted to effect the operative movement of said rod, one of said cross-heads operating positively on the rod to effect its preliminary movement, a yielding connection between the rod and the other cross-head and means for shifting the cross-heads, substantially as set forth. 125

4. In a glass-pressing apparatus, the combination of two cross-heads, means for shifting the cross-heads, a plunger, a plunger-actuating rod passing loosely through the cross- 130

heads, two shoulders or collars on said rod, one of which is so arranged that one of the cross-heads will have a positive bearing thereon, and a spring arranged between the other collar or shoulder and cross-head, substantially as set forth.

5. In a glass-pressing apparatus, the combination of a plunger, a plunger-actuating rod, two cross-heads, connections between the rod 10 and cross-heads, whereby one of the latter will apply a positive force to the rod and the other cross-head will apply a yielding force to the rod, and means for causing the cross-heads to operate successively, substantially 15 as set forth.

6. In a glass-pressing apparatus, the combination of a plunger, plunger-actuating mechanism, connections between the actuating mechanism and the plunger for imparting 20 to the plunger a positive unyielding initial movement and a secondary yielding movement, and means for permitting of the arrest of the plunger during this initial movement, upon meeting a substantially unyielding resistance, and the continuance of a yielding 25 pressure upon the glass within the mold during the remainder of the operation, substantially as set forth.

7. In a glass-pressing apparatus, the combination of a plunger, a plunger-actuating rod, two cross-heads adapted to successively effect 30

the operative movement of said rod, a connection between one of said cross-heads and the rod which is under normal operative conditions unyielding but which is adapted to 35 yield in case the plunger meets with a substantially unyielding resistance to its movement, whereby a positive initial movement is imparted to the plunger under normal operative conditions, but whereby the plunger 40 may be stopped in its initial movement upon meeting a substantially unyielding resistance to its initial movement; a connection between the other of said cross-heads and the rod which is normally yielding, whereby a final yielding 45 force is applied to the plunger; and means for causing the cross-heads to operate successively, substantially as set forth.

8. In a glass-pressing apparatus, the combination of two cross-heads, means for shifting the cross-heads, a plunger, a plunger-actuating rod passing freely through the cross-heads, two shoulders or collars on said rod, and springs arranged between the said cross-heads and said shoulders or collars, substantially 50 as set forth.

In testimony whereof I have hereunto set my hand.

GEORGE E. CLEVELAND.
